US00D845446S

(12) **United States Design Patent** (10) **Patent No.:** **US D845,446 S**
(45) **Date of Patent:** **** Apr. 9, 2019**

(54) **VENT**

(71) Applicant: **W. L. Gore & Associates, GmbH**,
Putzbrunn (DE)

D255,528 S 6/1980 Seager
4,517,262 A 5/1985 Beidler
4,689,281 A 8/1987 Dandona et al.
(Continued)

(72) Inventors: **Mike Seybel**, München (DE); **Joona Riihimaki**, München (DE); **Rainer Enggruber**, Gruenwald (DE)

FOREIGN PATENT DOCUMENTS

(73) Assignee: **W. L. Gore & Associates, GmbH**,
Putzbrunn (DE)

DE 102007050921 5/2009
EM 002342063-0003 2/2014

(Continued)

(**) Term: **15 Years**

(21) Appl. No.: **29/550,434**

(22) Filed: **Jan. 4, 2016**

FIG. 1 is a three-quarter top isometric view of a vent of the design of the present invention;

FIG. 2 is a front side view of the vent design of FIG. 1;

FIG. 3 is back side view of the vent design of FIG. 1;

FIG. 4 is a right side view of the vent design of FIG. 1;

FIG. 5 is a left side view of the vent design of FIG. 1;

FIG. 6 is a bottom view of the vent design of FIG. 1;

FIG. 7 is a top plan view of the vent design of FIG. 1; and,

FIG. 8 is a three-quarter bottom isometric view of the vent design of FIG. 1.

The broken lines on the top surface of the vent are directed to environment and are for illustrative purposes only; While all other broken lines depict portions of the vent that form no part of the claim. The broken lines form no part of the claimed design.

1 Claim, 8 Drawing Sheets
